2 Claims

ABSTRACT OF THE DISCLOSURE

A cathode-ray tube for the display of color television images employing a shadow mask supported within the envelope by resilient members which are secured to the mask by auxiliary members which bridge the corners of the mask.

The invention relates to a color television display cathode-ray tube provided with a shadow mask which has a protruding edge and is secured in the tube immediately in front of the display screen by means of resilient suspension members arranged in the proximity of the corners of the mask and extending substantially along the axis of the tube. The invention more particularly relates to such a tube in which the suspension members are shaped and arranged so that when the mask electrode is heated, a correction of the position of the apertures of this electrode relative to the color elements of the display screen is obtained.

In order to obtain a satisfactory correction upon heating of the mask, the suspension members used each have the form of a resilient strip and are located in the same plane as the tube axis but are at an angle of approximately 45° to said tube axis. An expansion of the mask then involves a pivotal movement of the suspension members about their supporting points on the glass wall so that the mask is slightly moved towards the display screen.

Since there is only a narrow space between the protruding edge of the mask and the glass bulb, only short and hence rigid strips can be arranged. Due to the small length of the strips, it is hardly possible to obtain a sufficient flexibility for the strips for inserting the mask electrodes into and removing them from the glass window during the manufacture of the display screen. The rigid strips are then soon bent beyond the limit of flexibility so that they may be permanently deformed. These disadvantages are avoided if, according to the invention, the strip-shaped suspension members arranged at the corners of the mask extend beyond the protruding edge of the mask and are secured on the inner side of the mask edge.

This end of each of the suspension members is preferably secured to an auxiliary member which bridges the corner of the mask. Especially if the mask is not provided with a supporting frame but if the protruding edge is formed on the mask itself, such an auxiliary member will also considerably strengthen the mask. The suspension member and the auxiliary member are entirely located within the part of the corner of the mask which is not struck by the electron beams.

2

It is known per se to secure a suspension member on the inner side of the curved edge of a circular mask, but in this case a pin-shaped member was passed from the bulb wall through an aperture in the mask edge and secured to the resilient member entirely located within this edge. A correction of the position of the mask relative to the display screen was not obtained.

The invention will be described with reference to the accompanying drawing, in which:

FIG. 1 is a sectional view of a corner of a window and mask with a securing member of known construction,

FIGS. 2 and 3 are similar sectional views of two embodiments according to the invention, and

FIG. 4 is a plan view of a corner of a window and mask as shown in FIG. 3.

Referring now to FIG. 1, reference numeral 1 denotes a glass window to the inner side of which is applied a luminescent screen 10. Immediately in front of the screen 10, a shadow mask 2 provided with a protruding edge with flange 3 is arranged in the tube. The space between the edge of the mask and the edge of the window accommodates a resilient member 4 which is located in the same plane as the tube axis and is at an angle of approximately 45° to said tube axis. Upon expansion of the

mask electrode 2, the resilient strip 4 pivots about the supporting point 5 at which the strip 4 bears on a cam of the window 1 so that the mask is moved towards the screen 10. However, the strip 4 can be only very short and is therefore rigid so that difficulties are involved in inserting the mask into and removing it from the window 1 several times during the manufacture of the screen 10.

The embodiment of FIG. 2 avoids these difficulties in that the resilient strip 4 is bent around the edge with flange 3 of the mask 2 and has a comparatively long resilient part which is at an angle of 45° to the tube axis. The end of the strip 4 is secured to an auxiliary member 6. This auxiliary member preferably bridges the corner of the mask, as is shown in FIG. 4, so that the mask electrode is considerably strengthened. The auxiliary member and the suspension member are entirely located within the part of the corner of the mask which is not struck by the electron beams 11.

In the embodiment shown in FIGS. 3 and 4, the resilient strip 4 is provided at one end with a pin 9 which is clamped in a recess 8 of a thickened part 7 of the glass wall of the window 1. The pin is centered in the recess 8 by means of a conical upper end and is fixed afterwards in the correct position when the cone is secured on the window, preferably by means of a readily melting kind of glass, as is common practice for color display tubes.

Although only two embodiments have been described, the suspension members may also be shaped differently without departing from the scope of the invention. For example, one end of the strip 4 may be bent so that it constitutes the auxiliary member 6.

What is claimed is:

1. A cathode ray tube for the display of color television images comprising, an envelope having a display screen, of the triad, phosphor dot type, a rectangular shadow mask in front of and spaced from the screen, said mask having a peripheral integral portion substantially parallel to the longitudinal axis of said tube and a support member bridging each of the corners of said portion at points remote from the peripheral edge, and a resilient

strip connecting each of said support members to a pin in said envelope wall, said strip comprising a portion extending from said pin substantially perpendicular to said longitudinal axis at least as far as said mask, and a connecting portion extending toward said support member at an angle of approximately 45° with said axis whereby expansion of said mask upon heating pivots said resilient members about said pins and moves said mask toward said screen.

2. A cathode ray tube as in claim 1 wherein said shadow mask further includes a radially extending rim integral with said peripheral edge.
